Attorney

UNITED STATES PATENT OFFICE

STEPHEN F. BRIGGS, OF MILWAUKEE, WISCONSIN, ASSIGNOR TO BRIGGS AND STRATTON CORPORATION, OF MILWAUKEE, WISCONSIN, A CORPORATION OF DELAWARE

LOCK

Application filed June 23, 1928. Serial No. 287,794.

This invention has for an object the provision of an improved lock of inexpensive structure in which the lock cylinder and cylinder mounting head is protected against intentional injury by an outer protective housing.

A more specific object of this invention resides in the provision of an improved lock structure having a bored base forming a mounting head in which the tumbler carrying lock cylinder is rotatably mounted and a casing member secured over the outer end of the mounting head to provide a shield therefor and maintain the cylinder therein.

With the above and other objects in view which will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawings, I have illustrated two complete examples of the physical embodiment of my invention constructed according to the best modes I have so far devised for the practical application of the principles thereof, and in which:

Figure 1 is a side elevational view, with parts broken away and in section, illustrating a lock structure embodying my invention, and

Figure 2 is a view similar to Figure 1 illustrating a slightly modified form of my invention.

Referring now more particularly to the accompanying drawings, in which like numerals designate like parts throughout the several views, 5 designates a lock cylinder mounting head having a central bore 6 extended throughout the major portion of its length and closed at its inner end 7, there being a transverse bore 8 communicating with

the inner end of bore 6 and intersecting its axis.

One end of the bore 8 communicates with the periphery of the mounting head 5 to permit the projection therebeyond of the end 9 of a locking pin or bolt 10 reciprocally mounted therein. The bolt 10 is preferably of cylindrical form having its medial portion milled or otherwise cut out, as at 11, and its inner end 12 counterbored to receive one end of a spring 13, the other end of which abuts the closed end of bore 8 to normally urge the locking bolt outwardly of the head 5. The bolt is actuated against its spring 13 to retract its end inwardly of the periphery of the mounting head 5 by a cam or projection 14 on the inner end of a lock cylinder 15 of conventional construction and rotatable within the bore 6. The cylinder carries suitable tumblers 16 which are normally sprung urged to engage in a longitudinal slot 17 in the wall of the bore, the tumblers being retracted within the plane of the cylinder by the insertion of a proper key 18 in its conventional key opening, not shown.

The outer end 19 of the cylinder extends beyond the outer end of head 5 and fits within a sealing cap 20 connected therewith for rotation by a projection or lug 21 on the outer end of the cylinder and engaged in one end of the cap key slot or opening 22 which aligns with the key receiving opening of the cylinder. The cap has an annular flange or shoulder 23 over which extends an annular flange or rib 24 struck inwardly from the outer end of a casing 25.

The inner end of the casing, in that form of my invention illustrated in Figure 1, is laterally flanged, as at 26, and fitted within a counterbore 27 at the base of the outer reduced portion 28 of the head 5 and there secured by spinning or crimping the material thereover, as at 29.

In that form of my invention illustrated in Figure 2, the casing 25 is of the same ex-

terior diameter as the inner end or base portion of the lock cylinder mounting head 5, and has a snug fit over the reduced portion 28 of the mounting head. The casing 25 is held against rotation with respect to the mounting head by a notch 30 in its inner edge which receives an elongation or projection 31 extended forwardly from the mounting head base, the casing being securely held on the reduced end of the mounting head by a split spring ring 32 engaged in registering annular grooves or channels 33 and 34 in the wall of the casing bore and the reduced portion 28 of the mounting head, respectively. The channel or groove 34 is of a depth equal to the full diameter of the split ring 32 to permit its contraction therein during assembling of the lock, as will be readily apparent.

From the foregoing description taken in connection with the accompanying drawings, it will be readily apparent to those skilled in the art to which an invention of the character described pertains, that I provide a novel and improved lock assembly in which labor costs are materially reduced, and in which a strong and more durable lock is provided to resist attempts to manipulate the same.

What I claim as my invention is:

1. In a lock, a lock cylinder mounting head having a central bore and a reduced end portion provided with an annular counter-bored shoulder at the inner end of the reduced end portion, a lock cylinder rotatable in the mounting head bore, means rotatably securing the lock cylinder in the mounting head and including a casing fitted over the reduced end portion of the head, a flange at the casing inner end and fitted within the counterbore of the mounting head shoulder, and a mounting head flange engaged over the casing flange to make the casing rigid with the mounting head.

2. In a lock, a lock cylinder mounting head bored from one end, a lock cylinder rotatable in the mounting head bore, means including an annular shoulder rotatably securing the lock cylinder in the mounting head and including a casing fitted over the bored end of the head with one end terminating intermediate the ends of the mounting head, and means securing the casing over the mounting head bored end.

3. In a lock, a lock cylinder mounting head having two external diameters and bored from its end of smaller diameter, a lock cylinder rotatable in the mounting head bore, a locking bolt slidable in a transverse bore in the mounting head end portion of larger diameter and adapted to have one end projected beyond the head periphery, means whereby rotation of the lock cylinder retracts the locking bolt within the mounting head, and means securing the lock cylinder within the mounting head against axial movement and including a casing engaged over the end

portion of the mounting head of smaller diameter and terminating adjacent the mounting head portion of larger diameter.

4. In a lock, a lock cylinder mounting head having two external diameters and bored from its end of smaller diameter, a lock cylinder rotatable in the mounting head bore, a locking bolt slidable in a transverse bore in the mounting head end portion of larger diameter and adapted to have one end projected beyond the head periphery, means whereby rotation of the lock cylinder retracts the locking bolt within the mounting head, means securing the lock cylinder within the mounting head against axial movement and including a casing engaged over the end portion of the mounting head of smaller diameter, and cooperating means between the casing and mounting head to non-detachably secure the casing thereover.

5. In a lock, a lock cylinder mounting head having a central bore and a reduced end portion provided with a counterbored shoulder at the inner end of the reduced end portion, a lock cylinder rotatable in the bore of the mounting head, an end cap engaging the outer end of the cylinder, a flange extended from said cap, a casing fitted over the reduced portion of the mounting head, a part carried by the outer end of the casing and engaging the flange of the end cap to secure it and the cylinder in place, a flange at the base of the casing and engaged within the counterbore of the mounting head shoulder, and a mounting head carried flange engaged over the casing flange to secure the lock assembly together.

6. In a lock, a lock cylinder mounting head bored from one end, a lock cylinder rotatable in the mounting head bore, a locking bolt slidable in a transverse bore in the mounting head and adapted to have one end projected beyond the mounting head periphery, means whereby rotation of the lock cylinder retracts the locking bolt within the mounting head, means securing the lock cylinder within the mounting head against axial movement and including a casing engaged over the bored end of the mounting head and terminating intermediate the ends of the mounting head, and cooperating means between the casing and mounting head to non-detachably secure the casing thereover.

7. In a lock, a bored mounting head, a flange on said mounting head, a rotatable cylinder in the mounting head bore carrying a flanged part near its front end, a casing having an inturned shoulder overlying the flanged cylinder carried part, and a shoulder on the casing and over which the mounting head flange is fitted to secure the casing to the mounting head and the cylinder in its bore.

8. In a lock, a bored mounting head, a flange on said mounting head, a rotatable cylinder in the mounting head bore having a shoulder, a member having a shoulder engag-

ing the shoulder of the cylinder, and a second shoulder on said member with which the flange of the mounting member is engageable to connect the member with the mounting member.

9. In a lock, a bored mounting member, a flange on said mounting member, a rotatable cylinder in the mounting member bore having a shoulder, a member retained by the mounting member flange and having shoulders and means cooperating with the shoulder of the cylinder and said last named member to secure the cylinder in the mounting member bore.

10 15 In testimony whereof I have hereunto affixed my signature.

STEPHEN F. BRIGGS.
